(57) **CLAIM**

The ornamental design for a display screen with icon, as shown and described.

DESCRIPTION

FIG. 1 is a front view of a display screen with icon showing the new design; and,

FIG. 2 is an enlarged view of the icon of FIG. 1.

The broken line showing of the display screen in FIG. 1 is for environmental purposes only and forms no part of the claimed design.

1 Claim, 1 Drawing Sheet

FIG. 1

FIG. 2
